UNITED STATES PATENT OFFICE.

LOUIS N. D. WILLIAMS, OF OGONTZ, PENNSYLVANIA, ASSIGNOR, BY DIRECT AND MESNE ASSIGNMENTS, TO SCOTT & WILLIAMS, INCORPORATED, OF CAMDEN, NEW JERSEY, A CORPORATION OF NEW JERSEY.

KNITTING-MACHINE.

1,116,190.

Specification of Letters Patent.

Patented Nov. 3, 1914.

Application filed October 6, 1909. Serial No. 521,360.

To all whom it may concern:

Be it known that I, LOUIS N. D. WILLIAMS, a citizen of the United States, residing in Ogontz, Pennsylvania, have invented 5 certain Improvements in Knitting-Machines, of which the following is a specification.

The object of my invention is to prevent 10 interference with the operation, or injury to the parts, of a knitting machine, due to contact of the closing latches of the needles with other needles, web holders or other elements of the machine. This object I attain 15 in the manner hereinafter set forth, reference being had to the accompanying drawing, in which—

Figure 1 is a view, partly in vertical section and partly in elevation, of sufficient of the parts of a rib knitting machine to illustrate 20 my present invention, and Fig. 2 is a face view of the same.

In the operation of an ordinary rib knitting machine the latches of each set of needles are closed by contact with the stitches 25 upon said needles, and, during the closing of the latches of the needles of one set, the needles of the other set are projected between the same, consequently, in the machines of the fine gages which are now in 30 use, there is liability of the latches of one set of needles to contact with the needles of the other set, or with web holders or other elements of the machine, because of the side 35 swing of the latches due to looseness of fit in the slots of the needles, or because of the lateral twisting of the needles in their grooves, the result being the injury or breakage of the latches or other elements of the machine, and consequent interference 40 with the proper operation of the machine. The same objections apply, in some measure, to knitting machines having but a single needle bed and intended for producing plain fabric. In order to overcome these objections, I provide for the closing of the 45 latches of the needles before they reach the stitches upon said needles and consequently before they are in position to contact with web holders or like elements of the machine, and, in a rib knitting machine, before they can contact with the needles of the other set.

By preference, I combine the latch closer with the yarn guide of the machine, the

latch closer thus located readily performing its intended function. In a rib knitting machine the latch closer preferably cooperates with those needles which constitute the primary needles whether the same be of the cylinder or dial, these primary needles 60 of the machine shown in the drawing being those of the cylinder.

The yarn guide 1 may be mounted and may feed the yarn α to the needles in the usual way, but the rear portion of the yarn 65 guide is cut away as shown at 2, so as to form a slot, and preferably an open-ended slot, in the guide, that member of the guide which is at the bottom of the slot having combined therewith a latch closing finger 3, 70 which may be either a tapered and inwardly deflected portion of said lower member of the guide or may be a separate piece secured thereto in any desired manner.

The latch closing finger is so located that 75 as the guide moves forward past the projected needles said finger will pass behind the lower ends of the depending latches and, as the needles are retracted, will engage said latches and close the same, as 80 shown in Fig. 2 of the drawing, the latch being completely closed, or the closing operation being so far completed, before the butt end of the latch reaches the level of the projecting interposed needles that there is 85 no possibility of contact of the closing latch with said interposed needles or with other and similarly located elements of the machine. During their closing movement, the 90 latches swing through the opening 2 in the yarn guide, consequently the latter offers no obstacle to said closing movement. It is not essential to my invention, however, that the latch closer should be carried by or constitute a part of the yarn guide, although such 95 a construction is preferred as the most convenient.

I claim:

1. A knitting machine yarn guide having a slot extending forwardly from the rear edge of the same adjacent to the lower edge of the guide, the member at the bottom of said slot having an upwardly directed but laterally bent upper portion for passing behind, engaging and raising the latches of the descending needles.

2. A knitting machine yarn guide having a slot extending forwardly from the rear

edge of the same adjacent to the lower edge of the guide, the member at the bottom of said slot having a latch closer for acting upon the retracting needles and the member 5 above the same having therein the guide opening for the yarn to be fed to the needles.

In testimony whereof, I have signed my

name to this specification, in the presence of two subscribing witnesses.

LOUIS N. D. WILLIAMS.
